WATER SEALED DOOR FOR BOTTOM-DISCHARGING RECEPTACLES

Anthony M. Meyerstein, Nutley, N. J., assignor of three-fourths to Rosoff Bros., Inc., Brooklyn, N. Y., a corporation of New York, and one-fourth to Anthony M. Meyerstein, Inc., New York, N. Y., a corporation of New York

Application July 30, 1936, Serial No. 93,349

5 Claims. (Cl. 110—171)

This invention relates to improvements in water-sealed doors for bottom-discharging receptacles and it has particular reference to the doors of an ash hopper such as may be used, for example, in connection with garbage and refuse incinerators, steam boilers and other combustion apparatus.

It is customary to provide such ash hoppers with doors which support the ashes until suitable conveyors for receiving and transporting the ashes are positioned below the hoppers. Before discharging the ashes from the hoppers they are quenched with water to extinguish any fires and also to cool the ashes somewhat for more convenient transportation. Such apparatus is frequently operated under forced draft at high temperatures and accordingly it is necessary to provide water-seals around the ash hopper discharge openings to prevent the escape of the hot air under pressure which would result in diminishing the available draft for the apparatus and also might cause injury to persons nearby.

An object of the present invention is to shape the doors, or gates, of the receptacle, or ash hopper, and to support them so their sides project above the lower edges of the discharge openings and, when the doors are closed, these sides are spaced slightly away from such edges so as to provide spaces for water seals extending completely around each discharge opening. No separate channels, or other members, are necessary in order to form, or to maintain, the water seals. The doors are suspended from bearings so that they may be easily swung from open to closed positions. There are no projections either on the receptacle or the doors which interfere with the movements of the doors or which necessitate the doors moving in other than simple arcuate paths. These bearings are located above the discharge openings and are therefore less likely to be subjected to grit and other injurious materials passing through the discharge openings. When fully opened the doors uncover the entire discharge openings to permit the ashes to drop freely from the ash hoppers.

Another object is to provide a construction in which the ash-quenching water may be used to form the water-seals. The doors are provided with side walls so that the water falling upon the ash-supporting surfaces of the doors collects there, and when it rises above the lower edges of the discharge openings of the hoppers, forms the water seals. Thus it is not necessary to supply water continuously in order to main-

tain the water seals. One of the side walls is lower than the others so that the excess water may flow away into a suitable trough without destroying the water seals.

A further object is to provide a trough into which the excess water from the doors may flow and be carried away under control.

Another object is to provide scraping means for cleaning the ash-supporting, or upper surfaces of the receptacle doors as they are moved to their open positions, thereby preventing the accumulation of ashes upon such surfaces and clogging of the apparatus. The opening of these doors separates all the surfaces between which the water-seals are formed so that there is no possibility of ashes accumulating in the water seal spaces and interfering with the proper maintenance of such water seals. The upper surfaces of the doors are preferably lined with fire-resisting material but the arrangement of parts is such that the water seals may be readily maintained even where these fire resisting linings have been worn away to a considerable extent. A further object is to provide means whereby the height of the water seal may be readily varied. Another object of the invention is to reduce the number of bearing surfaces necessary to support each door. This is accomplished by suspending each door in two bearings located above the discharge opening whereby the doors may be moved with little effort and without subjecting the bearings to injury due to the presence of grit or other foreign substances.

In the drawings accompanying and forming a part of this specification:

Fig. 1 is a side elevation of one embodiment of the present invention as applied to an ash hopper.

Fig. 2 is a cross sectional view substantially through the center line of a hopper with two doors, showing one door closed and the other open.

Fig. 3 is a cross sectional view taken substantially on the line 3—3 of Fig. 2, and

Fig. 4 is another sectional view taken substantially on the line 4—4 of Fig. 2.

The body of the ash hopper, or other receptacle to which the present invention may be applied, may be of any suitable design and may comprise, as shown in the drawings, four walls adapted to form a rectangular, closed container into which the ashes fall, or are forced from the grates. As shown in Fig. 1, the ash hopper walls are made up of the plates 1 supported by, and suitably fastened to, the angle bars 2, which also stiffen

these plates. The hopper is lined with fire resisting material, such for example, as the fire clay indicated at 3, which may be spread upon the plates 1, or fire bricks may be used to form the desired fire resisting lining. Channels 4, or members of other suitable design may be located on the sides of the hopper and in addition to reinforcing the walls of the hopper, are adapted to support the bearings for the doors, as hereinafter described. A framework 5 which may be constructed of channel members, extends around the lower end of the hopper and is adapted to support the members 6, the lower edges of which form the discharge openings of the ash hopper. The members 6 may be welded or otherwise secured to the framework 5 and supported thereby. As shown clearly in Figs. 2 and 3, the members 6 which may be castings, are provided with substantially parallel sides 7 having curved lower edges as illustrated. These edges may be, and preferably are, arcs of circles whose centers are at, or near, the axes of the bearings for the doors. The members 6 have rear depending walls 8, the lower edges of which act as scrapers 25 to remove the ashes from the surfaces of the doors as they are moved from closed to open positions. Additional scrapers 8' are provided outside of the side wall 7 and remove the ashes from the door surfaces between these side walls and the walls 14 of the doors.

As shown clearly in Figs. 2 and 4, a member 9, hereinafter designated as the separator, located in the lower part of the hopper, extends from one side of the hopper to the other and divides the discharge opening into two parts. This separator preferably has laterally and downwardly extending portions 10, the lower surfaces of which correspond approximately in contour with that of the sides 7 of the members 6. The separator 9 may have the configuration shown by the cross-section illustrated in Fig. 2, in which the lateral edges are bent upwardly, as indicated at 12, so that the upper surface of the separator is adapted to support fire-resisting clay, indicated at 11. The orifices through which the ashes are discharged from the hopper are bounded by the side walls 7, the rear walls, or scrapers 8, and the lateral edges of the separator 9. It will be noted that these edges are located above the lowest points of the side walls 7. The depth of the water seal may be readily varied by raising or lowering the lateral edges of the separator.

The doors 13 are preferably somewhat wider than the member 6 and are provided with side walls 14 which as shown clearly in Fig. 3, lie outside of the walls 7 on the lower part of the hopper and, when the doors are closed, rise above the curved lower edge of these walls (see Fig. 2). The rear walls 15 of the doors lie outside of the scraper walls 8 and project above the lower edges of these scrapers. If desired, these rear walls may have connected to them a web 16 with a hole 17 therein, or other suitable means may be provided whereby fastening devices may be attached to the doors to hold them open when it is desired to inspect, or repair, the apparatus. The front walls 18 of the doors have upper edges 19 which are offset and project slightly above the lowermost portions of the separator 9 and, when the doors are closed, underlie in close proximity the lower surfaces 10 of the separator as illustrated in Fig. 2.

The bottoms of the doors are preferably lined 75 with fire clay 20 and may have an arcuate sur-

face substantially concentric with the lower edges of the side walls 7. It will be readily apparent that this fire clay lining may have surfaces of other designs if desired, providing such surfaces do not offer projections which would interfere with the opening and closing of the doors.

The doors 13 may be supported in a number of ways but a convenient arrangement is shown in the drawings. These doors are supported in frames 21 rotatably supported in the bearings 22 which may be mounted upon the members 4 on the sides of the hopper. The lower parts of the door frames 21 may be riveted, or otherwise secured, to the doors 13, or may have inwardly extending, curved portions 23 to which the doors 15 may be fastened and upon which the doors may rest as shown clearly in Fig. 3. It will be observed that the bearings 22 are located substantially distances above the discharge openings and therefore away from the ashes passing through the hopper and thus are not subjected to grit or other deleterious material. Also, the bearings, so situated, are readily accessible for oiling, repair, etc.

The doors 13 may be opened and closed by means of the fluid-actuated plungers 24 operating in the cylinders 25. The ends of these plungers are provided with rollers 26 which operate in the links 27 attached to the front parts of the doors as shown. It will be observed that as the doors open the surfaces of the fire clay linings 20 move past the scraper members 8 so that these members force substantially all of the ashes off the doors. This arrangement prevents clogging of the apparatus. It will also be noted that as the doors are opened the component parts of the water-seals are removed from each other so that ashes cannot accumulate and clog the water-seals.

The doors are so formed that whether lined with fire clay to have an arcuate surface or not, water from the quenchers 28 in the sides of the hopper, collects on the surfaces of the doors and fills the spaces between the side walls 14 of the doors and the depending walls 7 of the hopper, also between the rear walls 15 and the scrapers 8 and underneath the separator 9. Thus a complete water seal is formed around each discharge opening. It will be observed that with the doors lined as illustrated a complete water seal is formed as soon as the water in the door reaches the lowermost edges of the separator 9.

When the doors are closed, the upper edges of the front walls 19 are lower than the upper edges of the side walls 14 and the rear walls 15. Thus excess water flowing through the hopper may spill over the front walls of the doors and fall into a trough 29 which lies under the hopper. The lower surface of this trough slopes downwardly from the central portion to the ends as illustrated in Fig. 4 so as to cause the water to flow into the headers 30 at each end of the trough, from which it flows to waste pipes. If desired, angle bars 31, or other suitable members, may be fastened to the front walls of the doors to prevent the water from clinging thereto and to direct the water into the trough.

I claim:

1. A hopper having side walls slightly converging toward the bottom and provided with a bottom-discharge opening and an arcuately movable water-sealed door therefor all of whose upper edges are outside and above the edges of the discharge opening when the door is in closed position and scrapers on the outside of the hopper walls 75

extending toward the adjacent sides of the door and adapted to remove some of the material discharged from the hopper from the space between the hopper walls and said door sides during opening movement of the door.

5 2. An ash hopper having a bottom-discharge opening and provided with a member dividing such opening into two parts, a water-sealed door for each part having an arcuate supporting surface for the ashes, portions of the under surface of said dividing member having substantially similar arcuate contours as the ash-supporting surface of each door, one edge of each door extending above the lower edge of the dividing member 10 but being lower than each of the other door edges whereby excess water may flow over said lower edge of each door while maintaining the water seal and a trough through which the excess water may be removed.

15 20 3. A hopper having a bottom-discharge opening and provided with a member dividing such opening into two parts, a trough located below and extending substantially parallel with said member, water-sealed doors adapted to close each part of said discharge opening, one edge of each door lying under said member when the doors are in closed position and being above the level of the lower edge of said member but lower than the other edges of that door whereby excess water will flow over said edge into the trough.

25 20 30 4. An ash hopper having a water-sealed bottom-discharge opening, a member extending transversely between opposite sides of the hop-

per and dividing said opening into two parts, the lower edges of said member forming the highest edges of each of said parts, an arcuately movable door for each part having parallel side walls outside of the hopper walls between which said member extends, and spaced therefrom, scrapers on the outside of said hopper walls adapted to remove ashes from the bottoms and said parallel walls of the doors as the latter are opened, a trough underlying said member, said doors being 10 provided with edge portions projecting between said member and trough, such edge portions of each door being lower than all the other edges of that door whereby excess water may flow into said trough while the water seal is maintained. 15

5 20 25 30 5. An ash hopper having a water-sealed bottom-discharge opening, a member dividing such opening into two parts, an arcuately movable water-sealed door for each discharge opening, provided with walls surrounding the lower edges of the hopper, one edge of each door extending slightly above the lower edge of said member but being lower than the other edges of that door to permit the escape of excess water thereover while the water seal is maintained, one edge of each 25 part of the hopper opening constituting a scraper for removing ashes from the underlying door and scrapers between the hopper walls and the respective adjacent walls of the doors adapted to remove ashes from that portion of each door outside of the hopper discharge opening for which the door is intended.

ANTHONY M. MEYERSTEIN.
